UNITED STATES PATENT OFFICE.

WALTER SCOTT, OF PLAINFIELD, NEW JERSEY.

SHEET-DELIVERY APPARATUS FOR PRINTING-PRESSES.

SPECIFICATION forming part of Letters Patent No. 439,306, dated October 28, 1890.

Application filed May 9, 1889. Serial No. 310,138. (No model.)

To all whom it may concern:

Be it known that I, WALTER SCOTT, of Plainfield, in the county of Union and State of New Jersey, have invented an Improved Method 5 of and Mechanism for Delivering and Folding Printed Sheets, of which the following is a specification.

This invention is especially adapted to the cutting and folding of printed sheets comprising the signatures for books or in cutting, folding, and delivering pamphlets and other printed matter requiring great accuracy in the cutting and folding. I make use of a cutter that perforates the paper at intervals 15 upon the line of fold, and I employ a folding-blade having a serrated or undulating edge, the projecting portions of which correspond in position to the perforations in the paper, so that the projections upon the folding-blade 20 pass into the perforations in the paper and accurately determine the position of the fold in the paper, and I provide a peculiar adjusting device for grasping and moving the sheet of paper to exactly the proper position 25 beneath the folding-blade, and I combine with these devices rotary perforators that partially or entirely separate the web of paper longitudinally either before the folding operation takes place or after the folding operation, and I also provide for separating the 30 web of paper into the proper lengths of sheet for the folding operations before mentioned.

In the drawings, Figure 1 is a general diagrammatic view representing my present improvements and the connections between the same and the printing-press. Fig. 2 is a plan view of the sheet in larger size, representing the lines of perforation and fold. Fig. 3 is a perspective view of the paper and the line of 35 perforations beneath the serrated edge of the folding-blade. Fig. 4 is a diagrammatic view in larger size of the mechanism for adjusting the paper beneath the folding-blade, and Fig. 40 5 is an elevation at one end of the gage and adjusting device.

L L' represent the plate or type cylinders, and M M' the impression-cylinders.

O O' are the cutting-cylinders, and upon these cutting-cylinders there are two sets of 50 cutters, the sets of cutters C being adapted to cut off the sheets or to perforate the paper,

leaving only sufficient intervening filaments for carrying the sheet along between the belts, so that the one sheet can be separated from the other by an accelerated movement, as 55 usual in printing-presses, upon the line where the perforations are made by these cutters C. The cutters B upon the cylinders O O' are adapted to penetrate the paper, forming incisions at intervals—say an inch long, more 60 or less—with a corresponding imperforated portion of the paper between the incisions, as the incisions made by the cutters B are to come upon the line of the fold made in the folding apparatus hereinafter described, and 65 upon reference to Fig. 2 it will be seen that the cutters C act at the ends of the printed sheets to allow one sheet to be separated from the next, and the cutters B act at the center of the sheet, where the first fold or crease is 70 made.

It is preferable to make use of tapes or belts 3 3 around rollers 4 and beneath the second-impression cylinder M' to hold the printed paper to such impression-cylinder 75 and to forward the printed paper to the cutting-cylinders O O', and during the passage of the paper from the impression-cylinder M to the cutting-cylinders O O' the paper receives a longitudinal range of perforations by the 80 circular cutter A, and these perforations are similar to those made by the cutters B, so that such perforations are upon the line of fold or crease subsequently given to the paper in the folding mechanism. These perforations made by the cutter A and the cutters 85 B weaken the paper upon the line of fold, so that the folding operation is performed more easily and accurately. As the sheet leaves the cutting-cylinders O O' it passes between 90 the ranges of belts or tapes 5 and 6, and these pass around and against the respective tape-rolls. If two printed sheets are to be imposed or laid one upon the other before being passed onto the folding mechanism, an imposing-cylinder R is made use of, as seen in 95 Fig. 1, the range of tapes or belts 5 passing over the roller D and down around the imposing-cylinder R and off to the rolls 58 10 9 8 D' 7, and the tapes 6 passing over the roll 100 D down below the roll 10 and off to the roll 14 13 12 15 11, and there is a switch S and guide-

5 fingers S', as in my patent No. 398,544, dated February 26, 1889, so as to cause one sheet to be wrapped around the imposing-cylinder R, and then a second sheet is imposed upon the same, 10 and the two sheets are passed off together to the folding mechanism. If, however, the separate sheets are to be delivered to the folding mechanism, the belts are arranged as in Fig. 15 6, the range of tapes 5 passing around the rolls 7, 8, 9, 10, and D and being provided with a tightener D', and the range of belts or tapes 6 passing around the rolls 11, 12, 13, 14, and 10, and the roll 15 may be made use of as a tightener, and the range of tapes or belts 16 pass around the rolls 2 14 18 and are provided with a tightener 19, and the range of tapes or belts 17 pass around the rolls 20, 21, and 13, and there is a switch at 22, by which the sheets are directed first to one folder 20 and then to the other, and it is now to be understood that as the printed and perforated sheets or web passes from the cutting-cylinders O O' between the rolls 7 and 11 and the ranges of tapes or belts 5 and 6 they are 25 carried to the roll D, and at such roll the tapes or belts nip the sheet, and if they have an accelerated velocity such ranges of belts pull one sheet off the web at the line of perforation made by the cutters C and forward such sheet to the folding mechanism, 30 such sheet passing around below the roll 10 and up between the belts 6 and 16, over the roller 14 to one folder, and the next sheet passes beneath the roll 10 and along upon the 35 range of tapes or belts 5 and over the roll 9 to the second folding mechanism, and it is to be understood that the folding devices hereinafter described as acting with the sheet of paper that passes along over the roller 14 are 40 duplicated and act upon sheets of paper passing along upon the tapes or belts 5 and over the roller 9.

45 I will now describe the devices for adjusting the position of the paper and for accurately folding the same.

50 P P' represent the first pair of folding-rolls, and above these there are bridge-plates 23 24, the bridge-plate 23 extending from the roll 18 to the roll P and the bridge-plate 24 being 55 above the roll P' and connected with the range of bars 25, so that the sheet as it is forwarded by the action of the ranges of belts or tapes 6 and 16, as they pass over the roll 14, is forwarded along upon the range of tapes 16 to the roller 18 and from there passes upon 60 the bridge-plate 23 and then upon the bridge-plate 24 and then upon the range of bars 25, and during this operation the sheet is below the tapes or belts 17; but the roll 13 is sufficiently above the tapes or belts 16 not to press 65 against such tapes or belts. Hence the sheet is left comparatively loose and free as soon as the rear ends thereof pass along above the roll 14, and the momentum of the sheet is easily arrested, and I make use of the devices hereinafter described for moving the sheet along to bring the perforations made by the

cutters B accurately beneath the folding-blade H.

70 Upon the cross-shaft 28 are arms 29, having between them a cross-shaft 30 with gripper-fingers 31. These gripper-fingers are closed by a spring and held open by a latch 33, which may be of any desired character. One of these arms 29 is projected upwardly 75 and acted upon by a spring and a cam J, so that the arms and grippers receive a slight oscillating movement, and the range 25 of bars is supported at this end by a cross-bar 34, and adjacent thereto is a fence or gage F 80 on a bar 36 between the arms 29, and the gripper-fingers 31 extend beyond the gage or fence F, so that when the front end of the sheet is arrested by the gage F the fingers 31 can be closed thereon and hold the sheet 85 against the bar 36.

85 To open and close the gripper-fingers, any usual mechanism may be made use of. I have shown a screw 40, passing through a stationary bracket, for opening the fingers as the 90 arm 41 from the gripper-shaft 30 comes in contact with such screw 40 upon the backward movement given by the cam J, and I have shown a screw 42 through the arm 43 for acting against the latch 33 to unlatch the 95 gripper-fingers at the extreme movement in the other direction to allow such gripper-fingers to close upon the sheet and grasp the same. It will be understood that the sheet as it lies between the ranges of tapes or belts 100 16 and 17 and upon the bars 25 is not confined, but can be carried down in the middle by the folding-blade H between the pair of rolls P P'; but to insure the complete movement of the sheet up to the gage or fence F 105 I make use of the roll G above the range 17 of tapes or belts, such roll G being upon arms from a rock-shaft 45 and acted upon at the proper time by the cam I so that such roll G presses the range of tapes 17 downwardly 110 upon the sheet, in order that the ranges of belts 16 and 17 may continue to forward the sheet until its advancing end reaches the gage F, at which time the roll G is raised by the cam I, and the belts 17 by their tension 115 rising from contact with the sheet leave such sheet against the gage F, and at this moment the gage F and arms 29, by the action of the spring and cam J, are moving slightly toward the sheet, and the screw 42 immediately unlatches the grippers and allows them to close upon the sheet, and then the cam J gives motion to the arms 29 in the opposite direction, drawing the sheet along gradually until the 120 perforations made by the cutters B are directly beneath the serrations in the folding-blade H, at which moment the arm 41 on the gripper-shaft comes into contact with the screw 40 and the grippers open, leaving the sheet in position for the folding-blade H to 125 act upon the same, and I remark that at this time it is preferable for the serrations of the folding-plate H to be in contact with the surface of the paper to slightly depress 130

such paper immediately adjoining the slits in such paper, so that the sheet will be held by such serrations in its exact position to be folded by the movement of the blade H. 5 If the roll G is made in sections acting between the tapes to press the sheet down upon the roll G', a slight tension will be applied to the sheet by the movement of the gripper-fingers after they have grasped the sheet. In 10 this instance the sheet will be drawn out smooth and flat, in consequence of the power derived from the tension of the sheet as it is drawn along between and gives motion to the rollers G G' and the inclined edges of the serrations adjust the sheet transversely at the same time that the fold is made. This folding-blade H may be moved by any suitable means. I have represented the cam J' as made use of for this purpose, and I remark 15 that the folding-blade H', made use of for folding the second sheet, can be connected with and receive its motion at the same time as the blade H, because the second sheet cut from the web has a less distance to travel and 20 will be in proper position for folding beneath the blade H' simultaneously with the first sheet beneath the folding-blade H. The sheet as it passes down between the first pair of folding-rolls P P' is carried by the ranges of tapes 25 or belts 50 and 51, the range of belts 50 passing around the roll P' and rolls 52 53 54 and the range of belts 51 passing around the roll P, 55, 56, and 57, and, if desired, at this point the sheet may receive a second transverse 30 fold by the blade H² acting upon the same and carrying the sheet down between the rollers 57 and 60, and the belts 51 will carry the folded sheet along below the third folder or creaser H³, to be carried down between the 35 folding-rolls H⁴ and delivered into the trough I², as usual, and where the sheet is to be divided longitudinally the circular cutter K is set sufficiently close to the roll 60 to cut entirely through the paper; but where the transverse fold is to be made at this line the circular cutter K, having upon its periphery penetrating-points, is set so as only to perforate the paper upon the line of the folding-blade H³. If the cutter K entirely separates the 40 sheet longitudinally, there will be two folding-blades H³ to fold the sheet at the lines 65, Fig. 2.

I have not represented the mechanism made use of in connection with the folding-blade H' or for acting upon the second sheet-delivery upon the range 9 of belts to such folding-blade H', because the devices before described in connection with the folding-blade H and the sheet after it has been folded thereby are 45 simply duplicated.

Any suitable gearing may be made use of for connecting and driving the respective parts. I have, however, indicated in the diagram a driving-shaft at 70, with a gear between the gears upon the cutting-cylinder O and the impression-cylinder M', and upon the shaft of the impression-cylinder M' is a bevel-

gear gearing to a similar wheel 71 upon the shaft 72, and there are bevel-gears at 73 upon the other end of shaft 72 and a train of gear-wheels giving motion to the shaft 75 and 74, upon which the cams I, J', and J are placed, and there is a train of gearing from the gear-wheel upon the cutting-cylinder O to drive the roll D with an accelerated movement, 75 and also to drive the roll 10 and the ranges of belts therewith connected. The gearing, however, may be varied, according to the arrangement of parts in the printing-press and the direction in which the sheets are carried 80 to the folding and delivery mechanism. The cutter or cutters that perforate the web longitudinally may be upon the cylinder O or O' and placed in the proper position in relation to the pages of printed matter on the 85 web of paper. The sheets may be entirely separated from the web by the cutters C, the diameter of the cylinders O and O' being in proportion to the type-cylinder, so as to cut the sheets of the proper size and perforate 90 the paper transversely of the web on the lines where the folds are to be made, and the circular cutter or cutters A perforate or separate the web longitudinally to prepare the same for the folders, as the folds will be more accurate than heretofore, because the cutters and perforators act directly upon the paper as it passes away from the impression-cylinder M.'

I claim as my invention—

1. The combination, in a machine for delivering and folding sheets from a web, of a cutter for nearly separating the sheet from the web by a transverse range of perforations, a cutter for perforating the sheet transversely 105 upon the line of fold, mechanism for separating the sheet from the web by an accelerated movement and for moving the sheet, a serrated folding-blade, the edge of which is in contact with the sheet and the serrations of 110 which correspond with the perforations in the paper, so that the sheet is arrested against the serrations of the folding-blade, and means for moving such folding-blade and forming a fold upon the line of perforations, substantially 115 as set forth.

2. The combination, in a sheet adjusting and folding mechanism, of a folding-blade, a gage and mechanism for carrying the sheet along automatically and bringing its advancing end against the gage or fence, grippers for seizing the end of the sheet, means for moving the gage, the grippers, and the sheet gradually until the sheet arrives at the proper position under the folding-blade, and 120 means for opening the grippers to allow the sheet to remain quiescent for the folding-blade to act upon the same, substantially as set forth.

3. The combination, in a sheet adjusting 130 and folding mechanism, of a folder and tapes or belts to convey the sheet to the folding mechanism, means for relieving the pressure of one set of tapes upon the sheet, so

that such tapes or belts cease to act thereon, grippers for grasping the sheet, and means for moving such sheet and grippers and for opening the grippers to drop the sheet when 5 in position for the action of the folding mechanism, substantially as set forth.

4. The method herein specified of accurately folding printed sheets, consisting in perforating the sheets on the lines of folds, moving 10 such sheets along to the position for being folded, and adjusting the sheet laterally by passing the blade having inclined-edged serrations into the perforations of the paper and folding the same by passing the paper between folding-rolls, substantially as set forth. 15

5. The combination, in a web printing and folding machine, of perforators for nearly separating the web at the ends of the sheet, perforators acting on the line of the fold, and a 20 folding-blade having projections corresponding with the perforations, so as to enter the openings in the paper and insure accuracy in the fold, substantially as specified.

6. In a folding mechanism, the combination, 25 with the conveying belts or tapes, of a gage for the end of the sheet, grippers to move and adjust such sheet, and means for moving and

opening the grippers and for folding the sheet, substantially as specified.

7. The combination, in a sheet delivery and 30 folding mechanism, of perforators to act upon the web at the lines of fold, and a folding-blade having serrations with inclined edges corresponding to the perforations, so as to adjust the sheet laterally by the folding-blade, 35 substantially as specified.

8. The combination, with the belts for conveying the sheet, of a press-roll, a gage and grippers, and means for moving the same to adjust the sheet and open and close the grippers, and mechanism acting on the sheet to fold the same, substantially as specified. 40

9. The combination, with the folding mechanism and the rock-shaft and arms, of a gage and grippers carried by the arms, and adjustable gripper-opening devices for adjusting the sheet in relation to the folder, substantially as specified. 45

Signed by me this 3d day of May, 1889.

WALTER SCOTT.
